Patented July 25, 1922.

UNITED STATES PATENT OFFICE.

CATHERINE B. LOCKWOOD, OF WASHINGTON, DISTRICT OF COLUMBIA.

DESIGN FOR A TOY DOLL.

61,273.

Specification for Design.

Patented July 25, 1922.

Application filed April 14, 1922. Serial No. 1,751. Term of patent 14 years.

To all whom it may concern:

Be it known that I, CATHERINE B. LOCKWOOD, a citizen of the United States, residing at Washington, District of Columbia, have invented a new, original, and ornamental Design for Toy Dolls, of which the following is a specification, reference being had to the accompanying drawing, forming part thereof.

The figure is a perspective view of a toy doll showing my new design.

I claim:

The ornamental design for a toy doll, as shown.

CATHERINE B. LOCKWOOD.
